OF BUFFALO, NEW YORK

INDEX DEVICE

Application filed November 9, 1928. Serial No. 318,219.

This invention relates to an index device and particularly to a card holder for use with a loose leaf binder so that a plurality of card holders may be arranged in a loose leaf binder in offset overlapping relation for visible indexing purposes.

The invention comprehends the provision of a plurality of card holders for loose-leaf binders in which each card holder is formed 10 of a holder sheet having means on a free marginal portion thereof for detachably retaining a record card and an attaching means or binding stub on an adjacent free margin adapted for detachable connection with the 15 binding mechanism of a loose leaf binder in such a manner that a plurality of card holders may be mounted in offset overlapping relation with the free marginal edges provided with the card holding means in visible relation for visible indexing purposes.

The invention further comprehends the provision of a card holder with an attaching or binding stub formed for engagement with a loose leaf binder so that it may be supported in the binder in any desired position in order that a plurality of card holders may be supported in offset overlapping relation and the attaching stub so formed that the connection between the attaching stub and 30 the loose leaf binder will control the spacing of the adjacent edges of adjacent card holders in order that the visible margin of each card holder may be varied to obtain the desired extent of the exposed portion of each 35 card holder.

In the drawing forming part of this application:

Fig. 1 is a plan view of a ring binder containing a number of card holders made in accordance with the invention arranged to offset overlapping relation for visible indexing.

Fig. 2 is a plan view of a card holder.

Fig. 3 is a fragmentary cross-section of a portion of the holder shown in Fig. 2 illustrating a celluloid sheath applied to one free margin of the card holder and a record card held in position by the sheath.

The card holder includes a holder sheet 1 of substantially rectangular form which is 50 provided adjacent its corner portions with a

group of diagonal slots 2 adapted to receive the corners of record cards for mounting on the rear side thereof, while diagonal slots 3 adjacent the upper corners of the holder sheet are adapted to receive the upper corners of 55 cards positioned on the front face of the holder sheet in a manner which will be more clearly described hereafter.

The lower margin of the holder sheet 1 as 60 illustrated in Figure 2 is formed with a plurality of perforations 4 in spaced aligned relation to provide a marginal section 5 on the holder sheet hingedly connected by the strips 6 to the remainder of the holder sheet. The formation of the perforations 4, disclosed 65 in Figure 2, provides the strips 6 which form the hinge connection between the marginal section 5 and the main body of the holder sheet.

A celluloid sheath 7 formed of a strip folded to provide a back portion 8 and a front portion 9 is placed over the marginal section 5 to enclose the free edge thereof, the back portion 8 of the sheath 7 being secured to the marginal section 5 by wire, staples or stitches 10. The marginal section 5 is provided with cut-out portions 11 at the point where the stitches 10 at the ends of the section 5 engage the rear portion 8 of the celluloid sheath in order that compensation may be made for differences in expansion between the section 5 and the celluloid sheath 7. The front portion 9 of the celluloid sheath is normally held in engagement with the section 5 by the natural resiliency of the celluloid material and is adapted to receive the lower marginal edge of a record card 12 as shown in Figure 3, the upper corners of the card being engaged in one of the slots 3 as illustrated in Figure 1. 70

The celluloid sheath 7 is formed of transparent celluloid so that the marginal edge of the card held by the sheath 9 may receive an index for visible indexing purposes in a manner well known in the art. When it is 75 desired to refer to the reverse side of a card thus mounted, the upper corners of the card are disengaged from the slots 3, and the card together with the section 5 is pivoted about the hinge connection formed by the perfora- 80 85 90 95 100

tions and strips 4, 6, whereupon a major portion of the rear face of the card is exposed for reference or recording.

The holder sheet 1 is formed with an extension to provide an attaching or binding stub 13 on one margin adjacent the marginal section 5 as shown in Figure 2. This attaching stub 13 may be hingedly connected to the main body of the holder sheet 1 by strips 14 formed by a series of aligned openings or slots 15 as shown in Figure 2.

A loose leaf binder is diagrammatically illustrated at 16 in Figure 1 having a back portion 17 and hinged covers 18. The back portion as illustrated carries a series of equally spaced binding rings or members 19 of any suitable type well known in the art. The attaching stub 13 is formed with a series of aligned openings 20 which are adapted to receive the binding rings 19, the openings 20 being spaced apart a distance equal to half the spacing of the rings 19. The spacing of the openings 20 is of a predetermined character as well as the spacing of the rings 19 in order that the card holders may be mounted in the binder in offset overlapping relation in the manner shown in Figure 1 and with one marginal portion of each card holder in visible relation. The spacing of the openings 20 and rings determines the extent of the exposed portion of each card holder and by varying the position of each card holder relative to the other by changing the openings 20 which receive rings 19, the width of the exposed margin of each card holder may be increased or decreased to a desired extent. By further having a specific relation between the spacing of the openings 20 and the rings 19 it will be seen that the card holders may be mounted in the binder so that the exposed margins of all of the card holders will be uniform, thereby facilitating visible indexing of the record cards detachably mounted in the card holders.

While the card holders as shown are associated with a ring binder it is to be understood that this is merely for the purpose of illustrating the application of the invention and that these card holders may be employed in any type of binder construction well known in the art where it is desired to use a series of card holders in offset overlapping relation for visible indexing purposes, the binding or attaching stubs 13 forming the parts which are used to secure each card holder in the binder by attachment with the binding mechanism of the type of binder construction desired.

What is claimed is:

1. A card holder for visible indexes comprising a sheet, means on one marginal portion for detachably holding a card, a hinge portion adjacent said means for permitting said card to be inverted without detaching it from said means, and an attaching stub on an-

other margin of said sheet adjacent said means.

2. A card holder for visible indexes, comprising a holder portion, means hingedly connected to one marginal edge of said holder portion for releasably holding a record card, and means on an adjacent margin for attachment to a support. 70

3. A card holder for visible indexes, comprising a holder portion, means hingedly connected to one marginal edge of said holder portion for releasably holding a record card, and an attaching stub on an adjacent marginal edge for connection with a support. 75

4. A card holder for visible indexes, comprising a holder portion, means hingedly connected to one marginal edge of said holder portion for releasably holding a record card, and an attaching stub hingedly connected to an adjacent marginal edge for attachment to a support. 80

5. A card holder for visible indexes, comprising a holder sheet formed to provide a hinge adjacent one marginal portion, means for releasably holding a card on said marginal portion, and another portion at an adjacent marginal edge forming a binding stub for attachment to a support. 90

6. A card holder for loose leaf binders, comprising a holder sheet formed to provide a hinge along one marginal portion, means releasably holding a card on said marginal portion, an adjacent marginal portion being formed to provide a hinge and a stub portion for support and attachment in a binder. 95

7. A card holder for loose leaf binders, comprising a holder sheet formed with a series of aligned perforations along one marginal portion to provide a hinged marginal section, a sheath enclosing said section and adapted to detachably hold a card therein, and a binding stub formed by an adjacent marginal portion of said holder sheet for attachment to a loose leaf binder. 100

8. In combination with a binder having a back portion provided with a series of binding rings, an index device comprising a plurality of sheets each having a record section and a binding stub hingedly connected thereto, said stubs being mounted on said rings to retain said sheets in overlapping offset relation with a marginal portion of each record section in visible index relation, whereby groups of sheets including the stubs may be turned over around said rings or said record sections may be individually hinged on their stubs independently of movement of their stubs. 110

9. In combination with a binder having a back portion provided with a series of binding rings, an index device comprising a plurality of sheets each having a record section and a stub hingedly connected to said record section, means on said record section for detachably retaining a card thereon, said stubs being movably mounted on said rings to re- 115

tain said sheets in overlapping offset relation with a marginal portion of each card on each record section in visible index relation, whereby groups of sheets including the cards thereon may be turned over around said rings or whereby said record sections and attached cards may be hinged on the stubs independently of movement of their stubs.

10. In combination with a binder having a back portion provided with a series of binding rings, an index device comprising a plurality of card holders each having a holder portion, a stub on one margin of the holder portion and a card-retaining portion on an adjacent margin of the holder portion, a hinge between said holder portion and said stub and a second hinge between said holder portion and said card-retaining portion, and means on said card-retaining portion for removably receiving a marginal portion of a record card with other portions of said record card overlying said holder portion; said stubs being movably mounted in said rings to retain said card holders in overlapping offset relation with the retaining portion of each in visible index relation, whereby one or more card holders may be selectively turned over on the rings or hinged and folded over their stub portions to expose the card on an underlying card holder, whereupon the card-retaining portion and attached card on the exposed holder may be hinged relative its holder portion to expose the reverse side of the card.
